CLAIM

The ornamental design for a container sidewall with end grip, as shown and described.

DESCRIPTION

FIG. 1 is a front elevational view of a container sidewall with end grip showing our new design, the rear elevational view is a mirror image thereto except for the threading on the neck which has the same appearance in the rear view as the front view;

FIG. 2 is a side elevational view showing the side with the end grip;

FIG. 3 is the opposing side elevational view, without the end grip;

FIG. 4 is a top plan view;

FIG. 5 is a front elevational view of an alternate embodiment of the container, sidewall with end grip, the rear elevational view is a mirror image thereto except for the threading on the neck which has the same appearance in the rear view as the front view; and,

FIG. 6 is a side elevational view of the alternative embodiment, showing the side with the end grip and ribs.
